UNITED STATES PATENT OFFICE.

FRANK E. RUSSELL, OF SAN FRANCISCO, CALIFORNIA.

BODY-BOLSTER AND DRAW-CASTING FOR TENDERS.

1,357,728.

Specification of Letters Patent.

Patented Nov. 2, 1920.

Application filed May 12, 1920. Serial No. 380,783.

To all whom it may concern:

Be it known that I, FRANK E. RUSSELL, a citizen of the United States, and a resident of San Francisco, in the county of San Francisco and State of California, have invented a certain new and useful Improvement in Body-Bolsters and Draw-Castings for Tenders, of which improvement the following is a specification.

10 My invention relates to locomotive tenders of the class or type in which the tank is of cylindrical form, and is supported on a structural steel frame, and its object is to provide simple and effective means for transferring draft and buffing strains from the draw casting to the tender frame, and imparting additional strength and stiffness to the overhanging portion of the frame between the body bolster supported on the 20 front truck and the draw and buffer casting, thereby preventing the drooping of the forward end of the frame and the loosening of the connections of the frame and draw casting members.

25 The improvement claimed is hereinafter fully set forth.

In the operation of tenders of the class above specified, considerable difficulty has been experienced in maintaining the draw 30 castings securely in position, this being due to the fact that the buffer casting being located at a level considerably higher than that of the draw casting, in order to clear the draw bar, a leverage action is exerted 35 upon the draw casting which pries it loose from the frame. A sufficiently extended period of service has demonstrated that this objection is satisfactorily overcome by my invention, and that collateral advantages in 40 promoting the strength of the forward portion of the frame and its connection are likewise attained.

In the accompanying drawings: Figure 1 is a vertical longitudinal central section 45 through the forward portion of a cylindrical tank locomotive tender, illustrating an application of my invention; Fig. 2, a half front view, partly in section; Fig. 3, a plan or top view of the combined body bolster, 50 and draw casting; Fig. 4, a vertical longitudinal section through the same; and, Figs. 5 and 6, transverse sections on the lines *a a* and *b b*, respectively, of Fig. 3.

In the practice of my invention, referring 55 descriptively to the specific embodiment thereof which is herein exemplified, I pro-

vide an integral structure, comprising a front draw casting, 1, located at one of its ends; a body bolster, 2, located at its opposite end; and two lateral connecting members, 3, 3, extending from the draw casting to the body bolster, said connecting members having lateral flanges, 3^a, 3^b, projecting outwardly at their lower ends. The draw casting, 1, is of the ordinary form with an eye, 1^a, at its middle for the reception of a coupling pin, 4, and the body bolster, 2, is inwardly segmentally curved on its top, in conformity with the curvature of the cylindrical tank, 5, of the tender, thereby forming a seat for the forward end of the tank. The lateral flanges of the connecting members, 3, 3, extend under those of the structural steel frame members, 6, of the tender frame, which are ordinarily of angle section, and the unitary draw casting and body bolster member is firmly secured to the webs and flanges of the tender frame members, by bolts passing through perforations, 3^b, in the webs and flanges of the connecting members. The body bolster is similarly bolted to the frame members, and is also bolted to the tank, 5.

The bumper casting, 7, is located relatively to the front draw casting, as in the ordinary construction, that is to say, at a sufficiently higher level to enable it to clear the draw bar.

For new applications, the draw casting, body bolster, and connecting members are 90 preferably formed in an integral casting, of the construction above described, but my invention may, without variation of structural or operative principle, be applied to existing equipment, by providing separate 95 connecting members, of the angle section shown, and securing them, at their ends, to the draw bar and the body bolster, by electric or acetylene welding, thereby preserving 100 the original castings, and embodying them in an integral structure. In such case, the weld at the forward ends of the connecting members follows the contour of the end flanges of the front draw casting, thereby affording a weld of greater length than if 105 made straight across the casting and correspondingly promoting its strength.

An annular wearing plate, 8, is interposed between the body bolster, 2, and the center plate, 9, of the front truck, being fitted in a central recess in the body bolster. Said plate is perforated for the passage of the

- center pin, 10, and may be prevented from turning in the body bolster, while readily removable therefrom, by a dowel pin secured in the body bolster, or in any other suitable 5 known manner. In addition to fulfilling the function of absorbing wear, the plate, 8, serves as a shim for maintaining the tender at the proper height to comply with Interstate Commerce Commission requirements.
- 10 It will be seen that, under the construction above described, such a strong and substantial connection of the front draw casting to the tender frame is afforded as will effectively resist the strains of draft and buffing 15 which are imposed on said casting out of line with its connection to the tender frame, and which therefore tend, with an action increased by leverage to loosen it from its normal rigid connection to the frame. A more 20 effective support for the forward end portion of the tender is also provided.
- I claim as my invention and desire to secure by Letters Patent:
1. The combination, with a cylindrical 25 tender tank, of a tender frame, and an integral structure comprising a front draw casting; a body bolster, having a curved tank seat at its top; and lateral connecting members, extending from the draw casting 30 to the body bolster, and rigidly connected to the forward portions of the frame members.
  2. The combination, with a cylindrical 35 tender tank, of a tender frame and an integral structure comprising a front draw casting, a body bolster, having a curved tank seat at its top; lateral connecting members, of angle section, extending from the draw
- casting to the body bolster; and connections rigidly securing said connecting members to the frame, through their bodies and their flanges. 40
3. The combination, with a cylindrical tender tank, of a tender frame, comprising side members of angle section; an integral 45 structure, comprising a front draw casting; a body bolster, having a curved tank seat at its top; and lateral connecting members, of angle sections, the flanges of which fit below those of the frame members; and bolts, securing the connecting members to the frame members, through the bodies and flanges of each of them. 50
4. The combination, with a cylindrical tender tank, of a tender frame; an integral 55 structure, rigidly secured thereto, and comprising a front draw casting, a body bolster, having a curved tank seat at its top; and lateral connecting members, extending from the draw casting to the body bolster; and a 60 bumper casting, connected to the tender frame, above the level of the draw casting.
5. The combination, with a cylindrical tender tank, of a tender frame; an integral 65 structure, rigidly secured thereto, and comprising a front draw casting, a body bolster, having a curved tank seat at its top; and lateral connecting members, extending from the draw casting to the body bolster; and an annular wearing plate fitted detachably 70 in the body bolster, and perforated for the passage of a center pin.

FRANK E. RUSSELL.
